AWNING

Peter M. Scatton, Philadelphia, Pa., assignor to Scatton Bros. Mfg. Co., Philadelphia, Pa., a partnership consisting of Michael J. Scatton, Peter M. Scatton, John P. Scatton, and Christina M. Scatton

Application April 24, 1956, Serial No. 41,187

Term of patent 14 years

(Cl. D21—6)

I claim:

The ornamental design for an awning, substantially as shown and described.
